UNITED STATES PATENT OFFICE.

GASPER LEON WADDELL, OF GRAPELAND, TEXAS.

EXTENSIBLE NECK-YOKE.

1,138,518.

Specification of Letters Patent.

Patented May 4, 1915.

Application filed May 26, 1914. Serial No. 841,161.

To all whom it may concern:

Be it known that I, GASPER L. WADDELL, a citizen of the United States, residing at Grapeland, in the county of Houston and 5 State of Texas, have invented new and useful Improvements in Extensible Neck-Yokes, of which the following is a specification.

The invention provides a neck yoke which 10 may be lengthened or shortened to meet varying conditions and has for its object to provide novel means for securing the adjustable sections in the required position, such means utilizing the strain upon the neck 15 yoke straps as means to prevent slipping, even though the main fastening means should become loose.

The invention consists of the novel features, details of construction and combination of parts, which hereinafter will be more particularly set forth, illustrated and claimed.

In the drawings hereto attached: Figure 1 is a detail view of a neck yoke embodying 25 the invention. Fig. 2 is a detail section. Fig. 3 is a detail view showing more clearly the fastening means whereby the movable sections are held in the adjusted position.

Corresponding and like parts are referred 30 to in the following description, and indicated in all the views of the drawings, by the same reference characters.

The neck yoke comprises a main section 1 and end sections 2 which are adjustable and 35 have telescopic connection with the main section to admit of the neck yoke being lengthened or shortened as required. The sections 1 and 2 may be of any construction and it is preferred to form the same of lengths of 40 tubing, the end sections 2 being of such relative size as to slide within the section 1. Rings 3 are attached to the outer ends of the sections 2 and are adapted to have the straps leading from the collar attached thereto. 45 The main section 1 may be attached to the pole or tongue in any manner to admit of the neck yoke having the usual movements. A longitudinal slot 4 is formed in a side of the section 1 and a plurality of notches 5 50 communicate with the rear edge of the slot 4 being formed in the edge portion of the section bordering upon the rear side of the

slot 4. Screws 6 are threaded into the sides of the sections 2 near their inner ends and are adapted to operate in the slot 4 and to 55 enter selected notches 5, thereby retaining the end sections 2 in the adjusted position. The heads of the screws 6 are adapted to overlap portions of the section 1 bordering upon the notches 5 so that when the screws 60 6 are tightened they are retained in the notches 5 and prevent possible slipping of the sections. Each of the rings 3 has a straight portion which passes through the section 2. The rings are positioned in such 65 a manner that when under strain incident to a pull upon the neck yoke they tend to turn the sections 2 so as to press or hold the screws 6 in the notches 5 thereby preventing possible slipping of the sections, even 70 though the screws 6 should become loose.

The neck yoke may be lengthened or shortened by loosening the screws 6 and turning the sections 2 to disengage the screws from the notches 5 after which the 75 sections 2 may be drawn outward or pushed inward and when the sections 2 have reached the desired position according to the required length of the neck yoke the sections 2 are turned backward to bring the screws 6 80 into registering notches 5 after which such screws are tightened to clamp the section 1 so as to hold the sections 2 in the adjusted position.

From the foregoing description, taken in 85 connection with the accompanying drawings, the advantages of the construction and of the method of operation will be readily apparent to those skilled in the art to which the invention appertains, and while I have 90 described the principle of operation of the invention, together with the device which I now consider to be the best embodiment thereof, I desire to have it understood that the device shown is merely illustrative, and 95 that such changes may be made when desired as are within the scope of the invention as claimed.

Having thus described the invention, what is claimed as new is:—

A neck yoke comprising a main section having a longitudinal slot and notches along one edge of the slot in communication therewith, and sections slidable within the main

section, screws threaded into the sides of the end sections and arranged to move from the longitudinal slot of the main section and enter selected notches thereof to hold the end sections in the adjusted position and rings fitted to the outer ends of the telescoping sections and arranged so that when under strain, the latter serves to hold the screws in

the receiving notches even though such screws should be loose. 10

In testimony whereof I affix my signature in presence of two witnesses.

GASPER LEON WADDELL.
